UNITED STATES PATENT OFFICE.

ALVA OWEN, OF CHICAGO, ILLINOIS.

TRUSS.

SPECIFICATION forming part of Letters Patent No. 399,433, dated March 12, 1889.

Application filed September 4, 1888. Serial No. 284,526. (No model.)

To all whom it may concern:

Be it known that I, ALVA OWEN, a citizen of the United States, residing at Chicago, in the county of Cook and State of Illinois, have 5 invented a new and useful Improvement in Trusses, of which the following is a specification.

My invention relates particularly to improvements in the pads used in trusses to 10 press against and hold the hernia in place.

It is a well-known fact that in ordinary 15 cases of hernia of the abdomen the most effective and comfortable pressure that can be brought against the viscera is that which the person himself is capable of exerting with his thumb; and it is my object to provide a 20 pad with a yielding central projection so constructed as to afford mechanically a pressure similar to that which may be exerted by the thumb, in the use of which there shall be no 25 danger at any time of the entrance of the projection into the rupture to an extent which would cause irritation, and whereby, should the projection become displaced, the viscera may be caught and held by the surrounding pad.

To this end my invention consists in the general construction of my improved truss- 30 pad; and it further consists in details of construction and combinations of parts, as hereinafter set forth.

In the drawings, Figure 1 is a perspective 35 view of a truss provided with a pad of my improved construction; Fig. 2, a section taken on the line 2 2 of Fig. 1, viewed in the direction of the arrows and enlarged, showing the retainers in their normal relative positions; and Fig. 3, a similar view, illustrating relative 40 positions of the retainers when the truss is adjusted upon the person of the wearer.

Although my improved truss-pad may be applied with advantage to any desired form of truss—as the elastic belt or spring-bow varieties—I prefer to employ my improvements 45 in connection with the former, as illustrated in the drawings, and I confine my description to such a truss, though without intending thereby to limit its application in a truss of any particular description.

50 A is an elastic belt carrying at one extremity a plate, B, provided with studs t t' , and at

its opposite extremity a plate, s, having an eye, s' , to engage the stud t . An elastic band, Δ' , is adjustably secured toward one end upon the belt A, as shown, and carries at its opposite extremity a plate, r, similar to the plate s upon the belt A, and having an eye, r' , to engage the stud t' .

C is a truss-pad, comprising a retainer, C', preferably of wood or hard rubber, having a 60 concave side forming a cup, q, and a flat base, x, and a yielding retainer, C². The retainer C' may be either round, as shown in Fig. 1, or of any other desired shape, and is preferably broadened around its edge, as shown, to 65 present a wide rim, h, for contact with the body when applied, as hereinafter described.

The plate B is provided with a round opening, into which a metal disk, p, of equal thickness with the plate and having a perforation 70 at its center and screw-holes at opposite sides, fits and is readily rotatable therein. A disk, o, somewhat larger in circumference than the disk p, is provided with screw-holes corresponding with those in the latter. The retainer C' is perforated through its center, and is also provided on its base x with screw-holes 75 to correspond with those in the disks p and o.

To secure the truss-pad C in place upon the plate B, the flat base x of the retainer C' is 80 placed against the inner side of the plate opposite the studs t t' , the disk p is inserted into the circular opening through the plate B, and the disk o is adjusted upon the outer side of the latter, with its screw-holes and those of 85 the disk p and retainer C' coincident, when the parts are secured together by means of the screws y y. The disk o and base x of the retainer C' being of greater circumference than the opening in the plate B, they are held 90 firmly in place on opposite sides of the latter, and the disk p, while it allows the pad to be turned, prevents any lateral movement thereof.

A sleeve, n, fits tightly and is rigidly held 95 in the perforation through the center of the retainer C' and disk p and projects into the cup q. The sleeve n is provided with a longitudinal slot, n', on one side, extending from toward the end embraced by the disk p to 100 toward the end which extends into the cup q.

The yielding retainer C² comprises a plate,

m, having an outer surface, *m'*, which is preferably convex, the plate *m* being of substantially the shape of the mouth of the retainer *C'* and arranged to enter the latter when compressed, as hereinafter described. At the outer side of the plate *m* is a rounded knob, *l*, preferably of hard rubber and slightly concave on its under side to fit the surface of the plate *m*. A rod, *k*, having a screw-threaded end, *k'*, and shoulders *k²* *k³*, extends at its opposite end into the sleeve *n*, where it carries a lug, *k⁴*, which enters the slot *n'*. The rod *k* may be moved longitudinally within the sleeve to an extent limited in its outward play by the impingement of the lug *k⁴* against the end of the slot *n'* and in its inward play by the impingement of the shoulder *k³* against the end of the sleeve *n*. The plate *m* is perforated at its center to fit over the threaded end *k'* of the rod *k* and rest against the shoulder *k²*. The knob *l* is provided at its center with a screw-threaded socket in its under side to receive the threaded end *k'* of the rod, and the knob is screwed upon the rod and clamps the plate *m* against the shoulder *k²*, whereby the parts are held rigidly together. A spiral spring, *i*, surrounds the rod *k* and protruding end of the sleeve *n*, resting at one extremity in a socket, *q'*, in the bottom of the retainer *C'*, and bearing at its opposite extremity against the under side of the plate *m*. The spring holds the retainer *C'* at the limit of outward play of the shaft *k*, as shown in Fig. 2, which is its normal position.

When the pad *C* is adjusted upon the body, the retainer *C'* surrounds the affected part, while the yielding retainer *C²* presses with its knob *l* into the rupture and its plate *m* against the surrounding parts.

The pressure which the yielding knob *l* exerts against the hernia is similar to that which

the person himself is capable of exerting with his thumb, and is similarly effective and comfortable, while the surface *m'* of the plate *m* affords a stop which limits the distance of the entrance of the knob, and the pressure of the surrounding retainer *C'* exerts a secondary holding effect. Should the knob *l* become displaced from its operative position by slipping in any direction, the annular concavity formed within the rim *h* of the retainer *C'* about the knob *l*, while the latter is pressed against the body with the stop *m'* as the base, will operate to catch the viscera and prevent their further protrusion.

What I claim as new, and desire to secure by Letters Patent, is—

1. A truss-pad comprising, in combination, a hollow retainer, *C'*, having an expanded rim, *h*, and a plate, *B*, upon which the retainer *C'* is secured and movable, and a yielding retainer, *C²*, having a projection, *l*, extending from near the center of the hollow retainer, and a stop, *m'*, surrounding the base of the projection, whereby, in case of displacement of the said projection, the viscera, wherever they shall protrude, may enter the hollow retainer, substantially as described.

2. A truss-pad comprising, in combination, a concave retainer, *C'*, provided with a sleeve, *n*, and a retainer, *C²*, comprising a plate, *m*, and projection *l*, secured together upon a rod, *k*, confined toward one end within the sleeve *n* and having limited longitudinal play therein, and a spring, *i*, surrounding the rod *k* and confined between the retainers *C'* and *C²*, substantially as described.

ALVA OWEN.

In presence of—

J. W. DYRENFORTH,
M. J. BOWERS.
